UNITED STATES PATENT OFFICE.

FRED HUBBARD, OF HUMBOLDT, ARIZONA.

BRAKE FOR CONVEYERS.

1,327,559.

Specification of Letters Patent.

Patented Jan. 6, 1920.

Application filed January 7, 1919. Serial No. 269,980.

To all whom it may concern:

Be it known that I, FRED HUBBARD, a citizen of the United States of America, residing at Humboldt, in the county of 5 Yavapai and State of Arizona, have invented new and useful Improvements in Brakes for Conveyers, of which the following is a specification.

The purpose of the invention is to provide 10 a device for use in conjunction with both single driven and tandem driven belts, whereby any retrograde movement on the part of the belts when the driving means therefor is at rest is avoided. A loaded 15 conveyer belt, when the driving medium for the same is stopped tends to creep backward and the present invention is a unique, efficient and inexpensive means readily attachable to the conveyer frame and engageable 20 with the belt during retrograde movement of the latter, the connection of this engagement being such that the belt is effectively stopped. On the forward movement of the belt however, the device idles 25 and in no way interferes with the efficient operation of the belt.

To the exact construction in which it is shown and described, the invention is not to be restricted. Continued use in practice 30 may make manifest certain desirable changes or alterations and the right is claimed to make any which do not deviate in scope from the subjoined claim.

The same numerals of reference designate 35 the same parts throughout the several figures of the drawings, wherein:

Figure 1 is a view in side elevation of the forward or delivery end of a conveyer belt, the attachment or brake being shown 40 in use therewith but in idling position.

Fig. 2 is a view similar to Fig. 1 but with the device in braking position to prevent retrograde movement of the belt.

Fig. 3 is an enlarged front elevational 45 view of the brake *per se*.

Fig. 4 is a side elevational view of the structure of Fig. 3.

The invention is shown in use as a medium for stopping retrograde movement of the 50 belt 1 the upper or delivery end of which is trained over the roller 2, back over the idle roller 3 and then forward over the forward idler 4, the latter as is usual being directly below the roller 2. The belt there- 55 after passes to the receiving end of the conveyer, being directed to the latter over the

idler 5. The belt 1 at the time of acting as a carrying medium is supported at uniformly spaced intervals by the rollers 6. All of the structure just described is characteristic of the outer form of belt conveyer and the structure as a whole is supported on the frame work 7, the diagonally disposed angle iron 8 which form bracing mediums for certain parts of the frame having attached 60 between them the device for performing the braking function when there is a tendency to retrograde movement on the part of the belt 1.

The angle irons 8, it will be observed are 70 disposed on that part of the frame between the rollers 3 and 4 and there is attached between these the round bar 9, the latter having its ends passed through suitable holes formed in the angles and having its ends 75 threaded for the attachment of nuts 10 which abut the two angles on opposite sides and in this way secure the bar 9 between them.

Swinging upon the bar 9 there are two 80 arms 11 which are united by means of a transverse plate 12, riveted or otherwise suitably secured to the two arms. Each of these arms is formed at its lower end with a bearing hub 13 in which there is journaled 85 one end of a shaft 14, the latter carrying a roller 15 which is fixedly secured to the shaft and abuts the two bearing hubs at its ends. The roller 15 is slightly longer than the belt 1 is wide and it lies upon the belt 90 adjacent to the roller 3, idling as is shown in Fig. 1 when the belt is moving forwardly and jamming between the roller 3 and the belt if the latter starts to move backward. The two arms 11 and the plate 12 constitute 95 a unitary structure for carrying the roller 15 and in order that the latter may be definitely positioned for engagement with the belt spaced washers 16 are mounted on the bar 1 between the arms 11 and the angle iron 8. 100 These washers successfully preclude any lateral movement of the frame comprising the arms and thus the roller 15 is kept in its proper position with reference to the belt.

The arms 15 are both provided with longitudinal slots 17 and the bar 9 passes through these slots, abutting the upper ends of the slots when the roller is in braking position and abutting the lower ends of the slots 110 when it is in idling position.

To provide for lubricating the journals

of the shaft 14, grease cups 18 are attached to the bearing hubs 13 for the obvious purpose of supplying the journals with lubricant.

- 5 The bar 9, it will be observed constitutes the axis of movement and is, as is apparent, offset from the axis of rotation of the roller 3. When the belt is moved forwardly, it will be passed from the bottom of the pulley 3 toward the top of the pulley 4 and its tendency therefore is to carry the roller 15 and its attendant frame in the same direction, when the frame is caused to rise so that the bar 9 stands against or adjacent to the bottom ends of the slots 17. The rollers are thus run free on the belt but in case the driving medium of the belt is stopped and the load carried thereon tends to carry the belt backwardly, the roller 15 and its
- 10 frame will be carried in the direction of the roller 3, the slot 17 permitting the frame to descend as it is carried in the direction of the roller 3. When the bar 9 abuts the upper ends of the slots 17 the roller 15 is thrown against the surface of the roller 3 with the result that there is a tendency to turn it and the roller 3 in opposite directions the belt the while tending to move in

the same direction. Consequently both rollers are stopped and the belt 1 is prevented from backward movement because of the resistance offered by the retarded rollers. While the invention has been described and illustrated as applied to a single conveyer belt, it is obvious that it is equally applicable to tandem belts in conjunction with which it serves the same purpose.

The invention having been described what is claimed as new and useful is:—

The combination of a frame, rollers rotatably mounted in the frame, a conveyer belt trained over said rollers, a secondary frame carried by the first said frame, the said secondary frame comprising arms in which there forms longitudinal slots, a bar mounted in the first said frame and passing through the slots, and a roller journaled in the secondary frame and bearing upon the belt, whereby the said frame may swing toward or away from one of the first said rollers so that the last said roller may idle upon the belt or jam between it and one of the first said rollers for the useful purpose herein specified.

In testimony whereof I affix my signature. 55
FRED HUBBARD.
